UNITED STATES PATENT OFFICE

2,473,032

MULTIFILTER ASSEMBLY FOR FILTERING
OIL OR LIQUIDSCamille Clare Sprankling Le Clair, Acton, London,
England, assignor to Tecalemit Limited, Brent-
ford, England, a corporation of Great BritainApplication March 15, 1945, Serial No. 582,883

3 Claims. (Cl. 210—168)

1

This invention relates to duplex filter apparatus, for use in filtering or cleaning oil or liquid, of the type in which each filter unit comprises a filter element contained within a container which is detachably attached to a head provided with inlet and outlet connections.

Where filter apparatus is fitted in an oil or liquid system designed for continuous operation over long periods, it becomes necessary to provide means whereby soiled filtering elements may be removed and replaced by clean ones while the apparatus of which it forms a part is still in operation.

To accomplish this it is known to fit two or more filters in parallel and to connect them up with control valves in such a way that any one or more may be isolated from the system for cleaning while the others remain in operation.

In practice it is not usual to fit more than two filters but even with only two filters the operations necessary to change over from one filter to the other are not simple and it is essential that they should be performed in their correct sequence because otherwise accidents or defective performance might occur. For instance, assuming that one filter is in use and the other filter is standing ready to be put into operation, it is necessary: to open the inlet to the filter not in use; to open the outlet from that filter; to close the inlet to the filter in use; to close the outlet from the filter in use; to remove the container and the used filter element from the filter previously in use; to clean out and fit a new filter element; to replace and secure the container in position and to prime the filter which is now empty, for which purpose it is necessary to vent the air entrapped to atmosphere so that it does not get into the oil or liquid system and thus cause trouble.

One object of the present invention therefore is to provide means whereby the above operations may be simplified, a second object being to provide locking means whereby it becomes impossible to open inadvertently any filter or filters which is or are in the working circuit.

For simplicity, oil and liquid will be referred to hereinafter as "liquid."

One constructional form of the invention is shown, by way of example, on the accompanying drawings, whereon:

Fig. 1 is an elevation, partly in section of the filter assembly;

Fig. 2 is a plan view;

Fig. 3 is a section on the line X—X in Fig. 2;

2

Fig. 4 is a plan view of the underside of the valve cover;

Fig. 5 is a plan view of the control valve;

Fig. 6 is a plan view of the valve plate;

Fig. 7 is a plan view of the underside of the valve plate;

Fig. 8 is a plan view of the carrier;

Fig. 9 is a plan view of the underside of the carrier;

Fig. 10 is a fragmentary plan view of the valve cover and shows the locking plate; and

Fig. 11 is a fragmentary enlarged view of the control valve operating handle.

Referring to the drawings:

This filter assembly comprises two spaced filters which, for the purpose of description, will be called "filter A" and "filter B." The duplex filter includes a common head which, for manufacturing reasons, is built up of three castings, namely a carrier 1, a valve cover 2 and a valve plate 3 between the carrier and cover, these parts being bolted together. Pressure-tight joints are formed between the adjacent faces of the carrier and the valve plate and between the adjacent faces of the valve plate and the valve cover by means of gaskets. The carrier is adapted to support two filter container bodies 4 and 4A of equal capacity, each of which is attached to the common head by means of a central holding bolt 5, the bottom end 15 of which is screwed into a boss 6 projecting upwardly from the bottom of the container body. Hand knobs 7 are attached to the top end of the bolts 5 and bear against the top of the valve cover 2 when the bolts are tightened up. Pressure-tight joints are formed between the top edges of the container body and the carrier 1 by means of joint washers 8 fitted in spaced annular recesses formed in the bottom face of the carrier 1. Filter elements 9 of known construction (for instance, 20 of the fabric type) are arranged in the container bodies between top pressure plates 10, fitted on hollow bosses 11 which project downwardly from the carrier 1, into the container bodies and the filter elements, and bottom pressure plates 12 which are pressed upwardly by springs 12A. The bosses 11 are bored to form oil outlet ports 13, see Figs. 1, 8 and 9, surrounding the bolts 5 from the interior of the respective filter elements 9. The holding bolts 5 pass upwardly through holes 14 and 14A in the valve plate, see Figs. 6 and 7, and also through hollow bosses 15 and 15A projecting downwardly from the valve cover 2. The carrier 1 is also formed with two spaced ports 16 and 17, of which the port 16 forms an oil inlet which communicates with the annular space 18, Fig. 1, be-

tween the filter element and container body of filter B, while the other port 17 forms an oil inlet which communicates with the equivalent annular space (not shown) between the filter element and container body of filter A.

The upper or valve cover part 2 of the head forms a chest and a cover for a disc type control valve 19, Figs. 3 and 5, which will be described hereinafter. The valve cover is formed with an oil inlet connection 20 which communicates with a large oil main inlet chamber 21 formed in the cover and surrounding the boss 15A, through which the holding bolt 5 of filter B is passed, and a central boss 22 which will be referred to hereinafter. Spaced from the said main inlet chamber 21 an arcuate oil outlet passage 23 is also formed in the valve cover and communicates with a main oil outlet connection 24 leading from the cover. Between the main outlet connection and the main inlet chamber there is a hole 25 in a boss 15 through which the holding bolt 5 of the filter A passes. As mentioned above, the valve cover 2 is superimposed upon the valve plate 3. The latter is formed on its upper surface with a shallow circular boss 26 which registers with the circular wall 26A of the main inlet chamber 21 in the valve cover, Figs. 3, 4 and 6. The top surface of the boss 26 is machined to form a flat valve face. Referring to Figs. 6 and 7, as viewed in plan, the boss 26 may be considered to be divided into seven equal sectors, and it is formed with a set of three adjacent sector-shaped outlet ports 27, 28 and 29, each occupying one sector, and a set of two adjacent sector-shaped inlet ports 30 and 31, each also occupying one sector, the two remaining sectors being left blank or unperforated. The outlet port 27 is adapted to communicate with the oil outlet 13 from filter A, the central port 28 of the set is adapted to communicate with the outlet passage 23 and the main outlet connection 24 from the valve cover 2, and the other port 29 is adapted to communicate with the oil outlet 13 from filter B. These ports are arranged alongside one another and are separated by ribs. The inlet port 30 is adapted to communicate with the said oil inlet 17 to filter A and the other inlet port 31 is adapted to communicate with the oil inlet 16 to filter B. These two inlet ports are also separated by a rib. The set of three outlet ports is separated from the set of two inlet ports by the two blank or unperforated sectors of the valve face, one sector being on either side. The inlet port 30 in the valve face communicates with the oil inlet port 17 to the filter A through a passage 33 formed in the underside of the valve plate 3. The inlet port 31 in the valve face communicates with the inlet port 16 to filter B through a similar passage 34 formed in the underside of the valve plate 3. Similarly, the outlet ports 27 and 29 in the valve face 26 communicate, respectively, with the outlets 13 from filter A and filter B via the passages 35 and 36 formed in the underside of the valve plate. The central or main outlet port 28 in the valve face 26 communicates with a peripheral passage 37 in the underside of the valve plate 3 which surrounds the aforesaid passages and is substantially of oval formation. This main outlet or peripheral passage 37 communicates at one end with an arcuate port 38 which registers with the aforesaid arcuate passage 23 in the valve cover 2 and, thus, with the outlet connection 24 from the latter. The above mentioned outlet passages 35 and 36, the peripheral main outlet passage 37 and the inlet passages 33 and 34 are all isolated or

separated from each other by ribs as shown in Fig. 7.

Referring to Fig. 5, the disc type control valve 19 is circular and, as shown in Fig. 3, is formed with a flat face 39 which is turnably mounted upon the valve face 26 of the valve plate 3. Like the valve face, the control valve may be considered to be divided into seven sectors, of which one 40 is left blank or unperforated and is flanked on one side by a sector-shaped inlet port 41 which is adapted to communicate with the inlet 17 to the filter A through the inlet port 30 and the passage 33 in the valve plate. On its opposite side, the blank sector is flanked by another sector-shaped inlet port 42, which is adapted to communicate with the inlet 16 to the filter B through the inlet port 31 and the passage 34 in the valve plate. Two of the other remaining four sectors of the control valve are apertured, connected, and enclosed by a housing 43 so as to form a transfer passage 44, which is flanked by, and is separated from, the said inlet ports by two further blank or unperforated sectors 45 and 46, one on either side.

Means are provided for turning the control valve through an angle of about 51°, i. e., through one of the aforesaid sectors. These means comprise a key having a spindle part 47, Fig. 3, which is turnably arranged in a hole 47A formed in the central boss 22 in the valve cover 2. The spindle part 47 of the key is integral with a flange 48 in which are formed two holes (not shown) into which two driving pins 49, Fig. 5, projecting upwards from the control valve 19, engage. A coil spring 50 housed in a recess 51 in the control valve reacts between the latter and the flange 48 of the key and thus acts to press the valve down upon its valve face 26 and also to press the flange into pressure-tight contact with a sealing washer 52 surrounding the spindle part of the key in the boss 22 in the valve cover 2.

The control valve is actuated by means of a hand lever 53 formed with a circular enlargement or heel at its inner end which, as shown in Figs. 10 and 11, is provided with a T-shaped opening 54, the metal of the stem part 55 of which is turned upwards to form a lug 56. The upper end 47B of the spindle part 47 of the key is flattened on two sides leaving a tongue like projection which engages in the cross part of the T-shaped opening formed in the heel of the hand lever 53 which heel is turnably arranged on the outside of the valve cover 2 upon a sealing washer 57 and in a recess formed in a sliding bolt plate and cover plate about to be described. The hand lever is secured in position laterally by its engagement with the top end of the spindle as explained above.

Immediately above the heel of the hand lever 53 a bolt plate 60, see particularly Fig. 10, is slidably mounted. The bolt plate comprises a central part 61 and two lugs 62 and 63 projecting from its opposite ends. A T-shaped aperture 64, see also Fig. 11, through which the top end of the key-spindle 47 projects is cut centrally in the central part. The cross part of the T lies longitudinally of the bolt and is sufficiently long to permit the bolt to move through its designed stroke without fouling the spindle, while the stem part 65 of the T lies transversely of the bolt and engages the lug 56 of the hand lever. The bolt plate 61 is held in position and guided by a cover plate 66 which is fixed to the valve cover 2 by screws 67 arranged on opposite sides of the bolt plate clear of the circular heel of the hand lever. At 75 its front end, the hand lever 53 is formed with a

Curved actuating handle part 53A which cooperates with two spaced stops 68 and 69 on the valve cover designed to limit the range of the turning movement of the hand lever 53 and, thereby, that of the control valve 19 to the aforesaid 51° approximately. The lug 62 on the bolt plate is adapted to engage in any one of a series of spaced recesses 70 formed in a flange 71 integral with the hand knob 7 attached to the holding bolt 5 of the filter A and the lug 63 on the bolt plate is adapted to engage in any one of a series of spaced recesses 72 formed in a flange 73 integral with the hand knob 7 attached to the holding bolt 5 of the filter B.

The purpose of the bolt plate 60 is to prevent either filter being opened when in operation. Thus, when the hand lever 53 is turned to the left as shown in Figs. 2, 10 and 11, the bolt plate is moved to the right by the engagement of the lug 66 with the slot 65, and the lug 63 engages in one of the recesses 72 in the flange 73, thereby preventing the filter B being opened. If the hand lever is moved to the right, the bolt plate 60 is moved to the left and the lug 62 is engaged in one of the recesses 70 in the flange 71, thereby preventing the filter A being opened.

Figs. 3 and 9 illustrate the means for priming the filters. These means comprise a priming valve having a flat valve face 74 of rubber or like material attached to a flange 75 provided with a stem 76 of metal or plastic material. The valve is slidably arranged in a hole formed in a boss 77 projecting forwards from the carrier 1 between the two container bodies 4 and 4A. This hole is closed by a hollow valve cover 78 which is screwed into the hole and is formed with a hole through which the valve stem 76 is slidable. The stem projects out of the cover and its outer end is attached to a hollow knurled knob 79 whereby the valve may be pulled off its port face 74A in opposition to a spring 80 which reacts between the cover and the flange 75 of the valve. The said port face is connected by two spaced right angled ports 81 and 82 to the two passages 33 and 34, Fig. 7, in the underside of the valve plate 3, which communicate respectively with the liquid system at the inlets 17 and 16 to the filters A and B.

Any air entrapped in the two filters A and B can be vented therefrom by means of two vent valves 84, Fig. 1, which allow air to escape from annular spaces 85 surrounding the holding bolts 5 within the aforesaid bosses 15 and 15A in the valve cover 2 through which the bolts pass. Each of the air vent valves is urged by a spring 86 onto its seat, which latter is formed at the bottom of a hollow valve body 87 screwed into the top of the hand knob 7 on the holding bolt 5. The valve body is provided with ports 88 communicating with atmosphere, and the said annular space 85 around the holding bolt 5 communicates with the hollow space 89 in the hand knob 7 below the valve 84 through a lateral port 90 and an axial passage 91 formed at the top end of the holding bolt. The valve stem 92 projects out of the valve body and thus provides a press button by which the valve may be opened.

The filter A is isolated from the system by pulling the handle end 53A of the control valve lever 53 in the direction of filter A against the stop 68 on that side of the valve cover. In these circumstances, the inlet port 30 in the valve face 26, which communicates through the passage 33 in the valve plate 3 with the port 17 in the carrier leading to filter A is masked by the blank

or unperforated sector 40 of the control valve 19, which lies between the two inlet ports 41 and 42 in the latter. The main oil inlet chamber 21 in the valve cover is, therefore, cut off from the inlet to the filter A. Simultaneously, however, the other inlet port 31 in the valve face 26, which communicates with the inlet to the filter B through the passage 34 in the valve plate 3 and through the inlet port 16 in the carrier, and which was previously masked by the blank or unperforated sector 40 of the control valve, now registers with the corresponding port 42 in the valve. Oil can then flow from the oil inlet chamber 21 in the valve cover 2 through the port 42, port 31 in the valve plate, passage 34 in the latter into the inlet to the filter B in the carrier 1. Further, the transfer passage 44 in the control valve 19, which, by spanning the main outlet port 28 and the port 27 in the valve face, previously provided communication between the main outlet port 28 and the outlet port 27 which communicates through the passage 35 in the valve plate with the outlet 13 from filter A in the carrier 1, is now moved so that, by spanning the main outlet port 28 and the outlet port 29 in the valve face, it provides communication between the said main outlet port 28 and the port 29 in the valve face communicating through the passage 36 in the valve plate with the outlet 13, from the filter B in the carrier 1. At the same time the blank segment 45 of the valve is moved into a position where it masks the outlet port 27 in the valve face thus cutting off the flow of outlet oil from filter A out of the passage 35 in the valve plate. In these circumstances, therefore, oil can pass as above described through the inlet and outlet passages of filter B which is thereby placed in operation, while on the other hand the inlet and outlet passages of filter A being masked, the latter is isolated from the system and ceases to operate. When the control valve 19 is turned in the direction indicated above, the lug 63 on the bolt plate 60 engages in one of the recesses 72 in the flange 73 of the hand knob 7 attached to the holding bolt 5 of the filter B and thus prevents that filter being opened inadvertently.

The control valve has only two operative positions, namely, one in which the hand lever 53 abuts against the stop 68, Fig. 10, in which position the filter A is isolated from the system as described above, and the other in which the hand lever abuts against the stop 69, in which position the filter B is isolated from the system.

In the latter position, the inlet port 31 in the valve plate is masked by the blank part 40 of the control valve so that oil cannot flow from the main oil inlet chamber 21 in the valve cover 2 through the inlet port 31 in the valve plate and thence to the inlet of the filter B through the port 16 in the carrier 1. The port 41 in the control valve, however, registers with the port 30 in the valve face 26, so that oil from the main inlet chamber 21 in the valve cover can flow into the inlet to the filter A through the ports 41, 30, passage 33 in the valve plate and the inlet port 17 in the carrier 1.

Further, as the transfer passage 43 in the control valve now spans the main outlet port 28 and the outlet port 27 in the valve face 26 oil can flow from the outlet from the filter A through the corresponding outlet port 13 in the carrier, passage 35, port 27, transfer passage 44 and port 28, in the valve plate to the main outlet passage 23 in the valve cover through the passage 31 and outlet port 38 in the valve plate.

On the other hand, in this position of the control valve, as the transfer passage 44 does not provide communication between the main outlet port 28 and the port 29, no oil from the outlet of the filter B can flow out of the passage 36 in the valve plate, the port 29 being masked by the blank part 46 of the valve.

While I have described and illustrated but one embodiment of my invention, it will be appreciated that numerous variations thereof can be made without departing from the spirit and scope of my invention, and, therefore, I desire to be limited only by the appended claims.

I claim:

1. A duplex filter of the class described, comprising a multi-unit common head, a carrier forming one of said head units, two spaced separate containers supported by said carrier, each container housing a filter element, said carrier being provided with spaced outlet ports communicating with the filter element outlets and with spaced inlet ports communicating with the filter element inlets, a valve plate forming a second of said head units and superimposed upon said carrier, said valve plate being provided with spaced outlet ports each of which communicates with one of said carrier outlet ports, said valve plate being provided with a main outlet port isolated from said first mentioned outlet ports and which communicates with an outlet passage formed in said valve plate, said valve plate being provided with spaced inlet ports each of which communicates with one of said carrier inlet ports, a valve cover forming a third of said head units and superimposed on said valve plate, said cover being formed with an inlet connection and a main inlet chamber in communication therewith and with said valve plate inlet ports, said cover being formed with an outlet passage in communication with said valve plate outlet passage, and a control valve turnably mounted on said valve plate controlling the flow of liquid through said valve plate ports, said control valve being provided with spaced inlet ports separated by an unperforated sector in face-to-face contact with said valve plate, said spacing being such that when one of said control valve inlet ports registers with one of said valve plate inlet ports, the other valve plate inlet port is masked by said unperforated sector, said control valve also being provided with a transfer passage in constant communication with said main outlet port in the valve plate and with one of said first mentioned valve plate outlet ports depending upon the position of the control valve, the arrangement being such that the inlet and

5 outlet of a single filter element are operatively connected to the inlet and outlet of the duplex filter.

2. A duplex filter of the class described, comprising a common head, two separate filter containers, a filter element mounted within each container, a central holding bolt passing through each container from the base thereof and through said head, each of said bolts being detachable from its associated container, a securing knob threaded on each of said bolts and in contact with said head to draw the associated container against said head, said securing knob having a part forming a locking element, a main inlet formed in said head, a main outlet formed in said head, valve means enclosed within said head and arranged to place the inlet and the outlet of one of said filter elements into communication with said main inlet and said main outlet, respectively, means projecting from said head and connected to said valve means to shift said valve means to place one or the other of said filter elements into operative condition, and a bolt plate associated with said valve shifting means and adapted to engage said locking elements, said bolt plate being operated to engage the locking element for the container which encloses the filter element in operative condition thereby preventing removal of this container, said bolt plate being simultaneously disengaged from the locking element for the other container thereby permitting removal of this latter container.

3. The combination set forth in claim 2, including means for releasing air entrapped in either filter element, said means comprising an air vent valve mounted in said securing knob, means projecting from said knob to open said vent valve, and a passage through said holding bolt and said head to the interior of said filter element through which the entrapped air may pass.
